US0D1092158S

(12) United States Design Patent (10) Patent No.: US D1,092,158 S
(45) Date of Patent: * Sep. 9, 2025

(54) CUTLERY

(71) Applicant: Sea to Summit Pty Ltd, Rivervale (AU)

(72) Inventors: Thomas M. Schilperoort, Perth (AU); Paramjeet Singh, Perth (AU)

(73) Assignee: Sea to Summit Pty Ltd, Rivervale (AU)

() Term: 15 Years

(21) Appl. No.: 29/874,130

(22) Filed: Apr. 14, 2023

(51) LOC (15) Cl. 07-03

(52) U.S. Cl.

USPC D7/653; D7/401.2

(58) Field of Classification Search

USPC D7/393, 395, 401.2, 642–645, 648–656, D7/664, 670, 688, 693, 696; D8/10, 12, D8/98, 99, 102, 105, 107, 300, 303
CPC A47G 21/004; A47G 21/005; A47G 21/02; A47G 21/023; A47G 21/026; A47G 21/04; A47G 21/06; A47G 21/061; A47G 21/062; A47G 21/065; A47G 21/08; A47J 43/28; A47J 43/281; A47J 43/282; A47J 43/283; A47J 43/285; A47J 43/288; B25G 1/00; B26B 1/02; B26B 3/00; B26B 3/02; B26B 3/03; B26B 3/06; B26B 5/00; B26B 7/00; B26B 9/00; B26B 9/02; B26B 11/00
